UNITED STATES PATENT OFFICE

JOSEF DORNBUSCH, OF KREFELD, GERMANY, ASSIGNOR TO LAMBERT & LOOMIS, INC.,
A CORPORATION OF NEW YORK

DESIGN FOR A TEXTILE FABRIC OR SIMILAR ARTICLE

Application filed January 27, 1931. Serial No. 38,457. Term of patent 3½ years.

To all whom it may concern:

Be it known that I, JOSEF DORNBUSCH, a citizen of Germany, and resident of the city of Krefeld and State of Prussia, Germany, have invented a new, original, and ornamental Design for Textile Fabric or Similar Article, of which the following is a specification.

In the accompanying drawing:—

The figure is a surface view of a piece of textile fabric or similar article with the design. The area within the dot and dash lines shows the unit of the design, which unit is repeated over the surface of the piece of fabric in the relation indicated by the extensions beyond the unit boundaries.

I claim:—

The ornamental design for textile fabric or similar article as shown and described.

Signed at Cologne, Germany, this 3 day of January A. D. 1931.

JOSEF DORNBUSCH.
